UNITED STATES PATENT OFFICE.

GEORGE TOBORG, OF CHICAGO, ILLINOIS.

AUTOMATIC FIREARM.

1,008,498.

Specification of Letters Patent. Patented Nov. 14, 1911.

Application filed February 1, 1911. Serial No. 605,886.

To all whom it may concern:

Be it known that I, GEORGE TOBORG, of Chicago, in the county of Cook and State of Illinois, have invented certain new and 5 useful Improvements in Automatic Firearms, of which the following is a specification.

My invention relates to that class of firearms in which a cartridge magazine is arranged in front of the breech under the barrel, and the chief object of my improvements is to provide means in conjunction with a recoil-operated, spring-pressed breech-block for passing the cartridges from the 10 magazine up to the barrel for firing.

Other objects will appear from the description of the mechanism and its mode of operation as presently given.

Said mechanism is illustrated in the accompanying drawings in which—

Figure 1 is a side elevation of a gun containing my invention, looked at on the left side. Fig. 2 is an enlarged fragmentary view partly in elevation and partly in section looked at on the right side. It shows a 22 rifle full size. Figs. 3 and 4 are detail cross sectional views taken on the respective lines 3 3 and 4 4 of Fig. 7 (Sheet 2). Fig. 5 is a fragmentary view in side elevation of 20 the chamber-frame having the side plate removed and looked at on the left side. Fig. 6 is a fragmentary longitudinal section through the frame and breech-block and showing the working parts below the breech-block in elevation and in the firing position. Fig. 7 is an axial sectional view similar to that shown in Fig. 6 but represents the working parts in the reverse position. Fig. 8 is a detail showing a horizontal section on 25 the line 8 8 of Fig. 7. Fig. 9 is a detail and shows a longitudinal section of the bottom plate of the frame with the trigger, sear, and hammer in elevation, looked at on the right side. Fig. 10 is a detail and shows a 30 similar view to that of Fig. 9 without the hammer and sear, and the sear-spring partly broken away. Fig. 11 is a detail and shows a fragment of the bottom plate of the frame in top plan view with the sear-spring and 35 trigger-spring broken away.

In the drawings 12 is the barrel, 13 the chambered stock-frame, 13^a a detachable side-plate of the frame, 14 the cartridge magazine, 15 the breech-block, and 16 the cartridge lifter for passing the cartridges from 40

the magazine up to the level of the barrel bore.

The breech-block 15 carries the firing-pin 15^a and is provided with a bore in which a coiled spring 15^b is arranged on a rod 15^c 60 which has a head threaded in the rear part of the frame. Said spring tends to hold the breech-block pressed against the front end of the frame over the barrel bore, and permit it to be thrown back against the rear end. 65

The cartridge lifter 16 is pivoted at its rear, 16^a, to the frame and preferably provided with a spring 16^b which tends to bear downwardly. The head or opposite end is thickened and chambered to receive the cartridge from the magazine when lowered. Fig. 8 shows a top view of the thickened head which is vertically divided longitudinally at the center and has the part 16^c hinged to the part 16^d as shown in dotted 75 lines, a cartridge being shown in the chamber. A spring 16^d mounted on the part 16 (Fig. 7) is adapted to bear against the farther rear edge of part 16^c so as to clamp the cartridge in the chamber, through said part 16^c slightly turning on its hinge pin 16^e. The extreme front end of the lifter is provided with downward extensions 16^f and the front end of the frame is provided with an inwardly-projecting wedge-shaped lug 80 16^g which is adapted to enter between the parts 16^f and spread open the chamber to receive the cartridge from the magazine when the lifter is being lowered. Said downward extensions further operate to prevent cartridges from coming out of the magazine when the lifter is raised to its limit. The location of the pivotal connection 16^a of the lifter 16 relatively to the barrel bore, the form of the lifter, and its 85 chamber end of the means employed to clamp the cartridge therein are such as to present the cartridge in level apposition to the barrel bore in front of the retracted breech-block and with its point free from 90 contact with the barrel, as seen in Fig. 7.

The breech-block at the top fills the chamber of the frame and normally covers the slot 13^b for the ejection of the exploded shells. Centrally it has a downward extension 15^d which is recessed at 15^e, the front end, to receive the cartridge rim. It also has a longitudinal groove 15^f (Fig. 4) for the part 16 of the lifter to work in. Said 95 downward extension passes through the 100 105 110

chamber of the lifter-head when the latter is raised. The breech-block has the usual extractor 15^g and opposite thereto a projection 15^h at the front end, and the interior 5 walls of the lifter-head chamber are provided with longitudinal grooves 16^h for said extractor and projection to pass in. This means is adapted to hold the cartridge in line with the barrel bore during the passage 10 of the breech-block forward to shove the cartridge into the barrel.

The cartridge chamber of the lifter is preferably made tapering from the rear to the front to fit the taper of the cartridge, 15 and the downward extension of the breech-block is adapted to fill said chamber at the rear and spread open the parts 16 and 16^c at the front against the action of the spring 16^d on its passage forward so as to let the 20 cartridge pass out. The said chamber is open at the top and the lines showing such opening at the surface preferably converge toward the forward end the same as do the interior walls of said chamber, and said 25 chamber is contracted at the rear end just enough to stop the backward movement of the cartridge properly in said chamber, but permit the forward movement of the breech-block through said chamber to shove the cartridge into the barrel.

At the rear of the lifter-head and just above the groove 16^h (Figs. 4 and 7), the part 16 of the lifter is provided with a bevel-pointed, spring bolt 16ⁱ which is adapted to 35 engage the extractor 15^g of the breech-block when the lifter is raised and the breech-block is thrown back, the bevel surface of said bolt on its upward movement striking the under side of the extractor and being thereby 40 thrown back and caused to spring forward and engage over the top of said extractor. (Fig. 4.) This means is provided in order to prevent the lifter-head from falling below the line of the barrel bore and to guide the 45 extractor and projection 15^h of the breech-block into the grooves 16^h of the lifter chamber. The walls of the lifter chamber are recessed at the front upper part (Fig. 8) so that after the extractor and projections 15^h 50 have passed through said grooves 16^h the lifter will be free to drop down when the breech-block is in its normal position pressed against the forward end of the frame and covering the cartridge in the barrel.

55 The lifter has a rigid arm 16^j at its rear end which is extended upward across the path of the breech-block and struck by the rear end of the breech-block when thrown back by the recoil of the firing. This over- 60 comes the downward pressure of the spring 16^h and causes the lifter-head to be raised so as to be caught and held up in line with the barrel by the engagement of spring bolt 16ⁱ with the extractor 15^g. The spring of the breech-block immediately causes the return

of the latter to normal and shoves the cartridge into the barrel but the firing does not occur until the trigger is pulled. The hammer 17 swings on a pin 17^a mounted on the bottom plate of the chamber frame under 7 the action of a main spring 17^b. It is thrown back into cocking position by the back action of the breech-block.

The sear 18 and trigger 19 are rabbeted together (Fig. 4) and pivoted on a pin 20 which is common to both but they have independent action. The trigger carries a spring locking bolt 19^a which is bevel-pointed and works in connection with a fixed cam 19^b on the wall of the slot in 8 which the trigger works. This bolt engages a projection 18^a of the sear and locks the sear to the trigger, during a portion of the operation and releases it during another portion of the operation. Separate springs 81 are provided, one 18^b adapted to bear on a shoulder of the sear and another 19^c adapted to bear on a shoulder of the trigger, both bearing downwardly and tending to cause the sear to turn toward and bear against the hammer (Fig. 9). The action is that when the trigger is being pulled so as to lift the point of the sear out of its notch in the hammer, the sear and trigger are locked and move together. This turn of the sear and 90 trigger on their pivot pin 20 causes the locking bolt to pass the cam 19^b and spring out of engagement with the projection 18^a so that the spring 18^b will cause the sear to turn back against the hammer independently of any further movement of the trigger. On release of the pulling on the trigger the spring 19^c will cause the locking bolt to pass the cam 19^b in the opposite direction and be thereby set in locking 10 engagement with the lug 18^a of the sear as before.

For cocking the gun by hand, I have provided a slide 21 having a push-rod 21^a adapted to pass through an opening in the 11 front piece of the frame and abut against the front end of the breech-block. Said rod is not attached to the breech-block. The slide is attached to the barrel so as to be movable thereon. It is preferably 11. adapted to fit over or upon the barrel and provided with inwardly-projecting pins 12^a adapted to travel in shallow grooves formed in opposite sides of the barrel for a short distance at the breech end. By taking 12^a hold of the slide and pulling it back the breech-block can be pushed back by hand for introducing the first cartridge into the barrel or withdrawing a cartridge in order to unload the gun without firing it. The 12^b slide is shoved forward by the first forward movement of the breech-block but is not otherwise affected by the action of the breech-block.

The numeral 22 Fig. 2 indicates the pro- 130

jecting end of a common turn key for locking the barrel to the chamber frame in lieu of threading the parts together.

The ejector 23 (Fig. 8) stands out so as to strike the rim of the shell when pulled back by the extractor 15^a and turn it out through the slot 13^b in the ordinary way.

I am aware that prior to my invention automatic firearms have been made with the frame and chamber in combination with the reciprocating breech-block, the latter and its travel being only partially covered by the chamber, the breech-block being projected beyond the chamber at the rear in action. I therefore do not claim such combination broadly, but—

What I claim is:

1. In an automatic firearm, the combination with the barrel, magazine and chambered frame, of a cartridge lifter consisting of the part 16 pivoted at its rear end to the frame within the chamber and a hinged part 16^c adapted to swing toward and from the part 16 at the front, the adjacent faces of said parts 16 and 16^c being recessed to form a cartridge chamber, a spring 16^d mounted on said part 16 and adapted to bear against the part 16^c, a downward extension at the front of the part 16^c, and a camlike lug 16^e on the front end of the frame, as specified.

2. In an automatic firearm, the combination with the barrel, magazine, and chambered frame, of a reciprocating, spring-pressed breech-block, a cartridge lifter having its rear end pivoted to the frame within its chamber and its front end having a cartridge holder and being vibratable across the path of the breech-block at the front, and locking means adapted to connect the lifter and breech-block slidably together, as specified.

3. In an automatic firearm, the combination with the frame provided with the chamber, of the reciprocating breech-block provided with a longitudinal bore, the chamber being adapted to completely inclose the breech-block in its travel, a coil spring within said bore and projected therefrom against the rear part of the chamber tending to force the breech-block squarely against the front of the frame, a spring-pressed hammer adapted to be set by the backward movement of the breech-block, a vibratable cartridge lifter adapted to move transversely to the movement of the breech-block and to

present the cartridge before the retracted breech-block in level apposition to the barrel bore, an angular upright arm connected with the lifter and extended up in the chamber behind the breech-block and near the end 60 of its backward travel for imparting upward movement to the lifter, and a trigger for setting and releasing the hammer, as specified.

4. In an automatic firearm, the combination with the barrel, cartridge magazine, and chambered frame, of a vibratable cartridge lifter provided with a grooved longitudinal cartridge chamber open at the ends and top and recessed at the front and above the 70 grooves, and a reciprocating breech-block provided with projections adapted to travel through said grooves and finally to pass the recesses when the breech-block is forward and the lifter is being lowered, as and for 75 the purposes specified.

5. In an automatic firearm, the combination with the chambered frame, barrel, and magazine, of a horizontally-reciprocating, spring-pressed breech-block arranged in the 80 upper part of the chamber, and a vertically-vibratable spring-pressed arm 16 pivoted near to the rear of the frame and carrying on its front end a cartridge lifter adapted to receive a cartridge from the magazine, and an 85 angular arm 16^j extended across the path of the breech-block near the rear of the chamber, as specified.

6. In an automatic firearm, the combination with the horizontal y-reciprocating 90 breech-block of a spring-pressed hammer adapted to be set by the recoil action of the breech-block, a sear and trigger mounted on a common shaft, and a spring-locking bolt mounted on the trigger and adapted to engage and release the sear, as and for the purpose specified.

7. In an automatic firearm, of the class described, the combination with the reciprocating breech-block, and the spring-pressed 100 hammer, of the trigger and sear provided with a spring locking bolt adapted to hold the sear and trigger in fixed relation while being pulled, and an independent spring 18^b for controlling the return action of the sear, 105 as specified.

GEORGE TOBORG.
